DESIGN FOR A NONROLLING TORQUE TOOL HANDLE

Hudson B. Roysher, Los Angeles, Calif.

Application November 29, 1947, Serial No. 142,873

Term of patent 14 years

(Cl. D93—4)

To all whom it may concern:

Be it known that I, Hudson B. Roysher, a citizen of the United States, residing at Los Angeles, county of Los Angeles, and State of California, have invented a new, original, and ornamental Design for a Nonrolling Torque Tool Handle, of which the following is a specification, reference being had to the accompanying drawing, forming part thereof.

Fig. 1 is an elevational view of a non-rolling torque tool handle showing my new design.

Fig. 2 is a sectional view taken along the line II—II of Fig. 1.

Fig. 3 is a sectional view taken along the line III—III of Fig. 1.

I claim:

The ornamental design for a nonrolling torque tool handle, substantially as shown.

HUDSON B. ROYSHER.
